UNITED STATES PATENT OFFICE

2,081,338

VENDING MACHINE

George Morrison, Poughkeepsie, N. Y.

Application July 19, 1935, Serial No. 32,247

1 Claim. (Cl. 194—98)

This invention relates to vending machines of that class which is shown and described in Patents Nos. 1,806,814 of May 26, 1931; 1,827,900 of Oct. 20, 1931; 1,864,847 of June 28, 1932 and 5 1,876,510 of Sept. 6, 1932, all of which were issued to me for vending machines and their parts, and the present invention relates more particularly to means for detecting the presence of slugs and counterfeit coins by exposing the same to the 10 view of the purchaser as well as to the next customer and the public, so that in this way should a person operate the machine with either a slug or counterfeit piece of money it will be placed on public view at once and will remain in view until 15 the next purchase is made.

In this manner the use of slugs and counterfeit 20 coins will be discouraged and detected at once.

The object of the present invention is to provide means whereby the coins as soon as they 25 have effected the tripping of the operating mechanism to allow the delivery to take place, will be exposed to view of the public.

Another object of the invention is to provide a simple, durable and fool proof machine, containing few parts and cheap to construct.

With these and other objects in view, my invention consists in certain novel construction and combination of parts that will hereinafter be fully described and claimed, and further illustrated in 30 the accompanying drawings which form a part hereof and in which like figures of reference refer to corresponding parts in all of the views, and it is understood that slight changes may be made without departing from the spirit of the invention.

In the drawings:

Figure 1 shows the front elevation of a vending machine showing my invention, but without the manually operated drive for the conveyor.

Figure 2 is a vertical sectional view of the same, but without the detailed lock and lock operating mechanism, as any of the styles shown and described in my above referred to patents may be employed.

Figure 3 shows a sectional view, taken on the line 3—3 of Figure 1, showing the coin exposing device.

Figure 4 is a sectional view taken on the line 4—4 of Figure 2, to illustrate the coin exposing device.

Figure 5 is an enlarged sectional view of a portion of the machine showing the application of the manually operated conveyor device.

Figure 6 is a partial cross sectional view of the 55 manually operated conveyor device.

Referring to the drawings:

As many of the parts shown are the same as those which were described in my Patent Number 1,876,510 I have for the sake of clearness and comparison, given them the same reference numbers as those used in the above patent, in which I show a frame composed of a base 10 to which are secured the two uprights 11 within which are rotatably mounted the transverse shafts 13 and 14, which carry the conveyor combination sprocket and gear wheels 15 for the conveyor chain 16, to which are attached the article supports 18 having the arms 19.

Upon the front or downward traveling part of the conveyor 16 these supports 18 are held in a horizontal position by the arms 19 contacting with the chain 16, and upon the rear or upward travel of the conveyor, these supports are folded against the chain out of the way, the machine being loaded from the front and no articles being supported upon the rear of the conveyor, and the length of chain being governed by the size and number of articles that the machine is to hold when loaded. The articles are placed upon the supports 18, and as the conveyor travels downward are deposited one by one upon the slotted shelf 59 by the fingers of the supports 18 in such a manner that they may be removed by the purchaser through the opening 70 in the front of the casing 71. Any desired size, shape and design of casing may be 30 employed.

The lock employed in this form of the machine is the same as that shown and described in my Patent No. 1,876,510 and comprises the coin entering slot 39 in the coin runway 38; the push rod 37; the lock 42, and operating mechanism therefor.

For receiving the coins 40 as they leave the lock after having released the same, and for exposing them to the view of the public, I have provided at a point below the shaft 13 and rotatably mounted in the upright 11, a shaft 72, and on the same plane therewith and in the forward end of the casing 71, I have placed another parallel shaft 73, and upon these shafts 72 and 73 there is mounted upon the rollers an endless belt coin conveyor 74, which is operated by a sprocket wheel 76 mounted upon the shaft 72 and driven by a chain 77 from a sprocket wheel 78 mounted on the shaft 13, in such a manner that the belt 45 conveyor 74 will travel the required distance forward for each discharge or vending movement of the article conveyor 16, or a sufficient distance 50 so that the coins 40 as they are discharged from the chute 38 will drop upon the coin conveyor 55

14 and be exposed through the glass table 79, remaining upon the conveyor 74 until the next purchase takes place at which time they will drop into the coin box 50.

5 In my Patent No. 1,876,510 and as shown in Figures 1, 2, 3 and 4 of this application, the article conveyor 16 is operated by gravity caused by the weight of the articles being vended, but in the modified and preferred form shown in the Figures 10 and 6, the article conveyor 16 is operated in a positive manner by a hand lever 81, operated by the purchaser.

This hand lever 81 is pivoted at its lower end as at 82 to the casing 71 or some other part of 15 the machine and may be reciprocated through the guide slot 83 formed in the glass table 79, or other part of the casing; and in its normal position a portion of it contacts with the end of the plunger 31.

20 To the upper portion of the lock plate 23 are secured two brackets 84 having transverse bearings within which are freely rotatably mounted the shafts 85 which carry the flanged guide rollers 86 which support and guide a toothed rack 87, which is in mesh with and is adapted to rotate a spur gear 88 freely rotatably mounted on a shaft 89 located in the upright 11.

To this same shaft 89 is secured in a rigid manner a ratchet wheel 90 engaged by a pawl 91 mounted on the side of the gear 88, in such a manner that by the movement of the rack 87 in one direction the pawl 91 will engage the ratchet 90 and drive the shaft 89, while when the rack 87 is moved in the opposite direction the pawl 91 will travel over the teeth of the ratchet 90 and the shaft 89 will remain idle.

Upon this shaft 89 is also secured a spur gear 92 which is in mesh with and rotates the combined sprocket and gear 15 upon which the conveyor 16 is mounted.

For reciprocating the rack 87, there is provided an arm 93 which is pivoted at its lower end as at 94 to the plate 23 and is connected at its upper end to the rack 87 by a link 95.

45 To normally retain the rack 87 in the position shown in Figure 5, the arm 93 is provided with a transverse hole 96 through which extends one end of a rod 97 which is slidably mounted in a bearing 98 on the plate 23; said rod 97 having a head 99 held in contact with the arm 93 by a spring 100 and stop 101 mounted on said rod 97; the inner end of the rod 97 contacting with a pin 102 on the release wheel 24; said arm 93 held under tension by the spring 103 attached 55 thereto and to the plate 23.

To actuate the arm 93 against the tension of

the spring 103 for the purpose of moving the rack 87 inward, there is provided a rod 122, the outer end of which is pivoted as at 123 to the hand lever 81, and the inner end of which is slidably mounted in a bearing 106 attached to the 5 end of one of the shafts 85, and abutting the arm 93.

The proper coin 40 having been inserted into the slot 39 to release the lock mechanism which is described in my Patents Nos. 1,827,900 and 10 1,864,847, the operator pushes inward on the hand lever 81 toward the casing 71, which in turn presses inward on the end of the plunger 31 to operate the escapement, and at the same time moves inward on the rod 122 causing the 15 arm 93 to move inward toward the back of the machine and carrying with it the rack 87 which rotates the gear 88 to release the rod 97 from the pin 102, allowing the escapement to operate, as a brake only.

20 After the hand lever 81 has reached the limit of its inward movement, it is pulled outward or back to its original position and on this outward travel the gear 88 by the action of the pawl 91 and the ratchet 90 will rotate the shaft 89 and 25 thereby the gears 92 and 15 imparting a positive downward movement to the conveyor 16 to bring the articles into a delivery position, one at a time.

It will thus be seen that in this manner the 30 action of the conveyor is rendered positive and the weight of the articles to be vended is not depended upon to move the conveyor.

The gravity method was not positive as the 35 weight of the articles varied and grew less as they were removed.

Having thus described my invention, what I claim, as new and desire to secure by Letters Patent, is:

In a coin display means for vending machines 40 comprising a casing, a transparent shelf carried and forming a part of the casing, a coin receiving chute adjacent one end of the shelf, an endless coin receiving belt in the casing, a coin storage chamber beneath the belt, said belt being of a width greater than the diameters of the coins deposited thereon and having an unobstructed surface adapted to have its upper stretch presented under the coin chute to receive the coins thereon in various positions before being conveyed to the storage chamber, said belt having its side edges spaced from the side walls of the casing a distance less than the diameters of the coins, and means for imparting movement to the belt. 45 50 55

GEORGE MORRISON.
